CLAIM

The ornamental design for an aircraft vanity, as shown and described.

DESCRIPTION

FIG. 1 is a front perspective view of an aircraft vanity showing our new design in an aircraft cabin;

FIG. 2 is a front view showing the aircraft vanity of FIG. 1; FIG. 3 is a perspective view showing the aircraft vanity of FIG. 1;

FIG. 4 is a side view showing the aircraft vanity of FIG. 1; FIG. 5 is another perspective view showing the aircraft vanity of FIG. 1;

FIG. 6 is a side view, opposite the side view of FIG. 1, showing the aircraft vanity of FIG. 1;

FIG. 7 is a top view showing the aircraft vanity of FIG. 1; and,

FIG. 8 is a perspective view showing the aircraft vanity of FIG. 1 with respect to an aircraft cabin.

In FIGS. 1-8, broken lines indicate environmental structure that forms no part of the claimed design.

1 Claim, 8 Drawing Sheets
